One O'Pain's Improved Cork Bottle

Patented Nov. 9, 1864

NO PRINTED COPY OF SPECIFICATION IN OFFICE.

Dec. 1997

Geo. G. Percival, M.D. of Brooklyn, N.Y.

Letters Patent No. 1997 Dated Nov. 8, 1864

Design for an Ink Bottle.

The schedule referred to in these Letters Patent and making part of the same.

It all whom it may concern:

Be it known that George G. Percival, M.D. of Brooklyn, in the County of Kings and State of New York, has invented or produced a new and ornamental Design for an Ink Bottle; and I do hereby declare that the following is a full, clear and exact description thereof, which will enable others skilled in the art to make and use the same in reference being had to the accompanying drawing forming part of this specification, in which:

Figure 1. is a perspective view of this invention.

Figure 2. is a transverse vertical section of the same.

Similar letters of reference indicate like parts.

This invention relates to a design for an ink bottle which is provided with a rounded top crater-like central depression, from the bottom of which rises the neck, representing a tower rising from a circular ditch.

The body A of my ink bottle, which is made of glass, stone ware or other suitable material, is provided with a rounded top, the central part of which is depressed to form a conical crater-like ditch as clearly shown in the drawing.

From the bottom of this ditch rises the neck c,

DES. 1997

2 representing a tower which is surrounded by a ditch.

The bottom of the ditch, where it joins the neck or tower is slightly rounded, as clearly shown in fig. 3 of the drawing and the top edge of the ditch is rounded also as previously stated, giving to the whole a neat and pleasing appearance.

The tower itself is cylindrical and its top cap is also rounded by a bend. A.

Claim as new and desire to secure by letters Patent
The design for an ink bottle as shown and described.
